L. B. CRAIG,
LUNETTE BRACKET.
APPLICATION FILED NOV. 3, 1920.

1,423,196.

Patented July 18, 1922.

INVENTOR.

Louis B. Craig

UNITED STATES PATENT OFFICE.

LOUIS B. CRAIG, OF DAVENPORT, IOWA.

LUNETTE BRACKET.

1,423,196.

Specification of Letters Patent. Patented July 18, 1922.

Application filed November 3, 1920. Serial No. 421,608.

(FILED UNDER THE ACT OF MARCH 3, 1883, 22 STAT. L., 625.)

To all whom it may concern:

Be it known that I, LOUIS B. CRAIG, a citizen of the United States, and a resident of Davenport, county of Scott, State of 5 Iowa, have invented an Improvement in Lunette Brackets, of which the following is a specification.

The invention described herein may be used by the Government, or any of its officers or employees in prosecution of work for the Government, or by any other person in 10 the United States, without payment to me of any royalty thereon.

The subject of this invention is a lunette 15 bracket intended primarily for attachment to the middle rail of a caisson to hold the lunette, though capable of use on other vehicles.

The main object of the invention is the 20 provision of a bracket which is simple, durable, and efficient and to which the lunette may be readily attached and from which it may be readily detached.

With these and other objects in view, the 25 invention resides in the novel arrangement and combination of parts and in the details of construction hereinafter described and claimed, it being understood that changes in the precise embodiment of the invention 30 herein disclosed may be made within the scope of what is claimed without departing from the spirit of the invention.

A practical embodiment of the invention 35 is illustrated in the accompanying drawing, wherein:—

Figure 1 is a fragmentary plan view of the middle rail of a caisson with a bracket 40 constructed in accordance with the invention in place thereon and a lunette attached;

Figure 2 is a side elevation of the same;

Figure 3 is a plan view of the lunette detached; and

Figure 4 is a side elevation of the bracket.

Referring to the drawings by numerals of 45 reference the forward end of the middle rail of a caisson is designated by the reference numeral 10 and to the end of this rail is secured the lunette bracket 11.

The bracket is, preferably, formed of 50 metal to provide upper and lower spaced apart plates bridged by a preferably curved portion 11'. The plates are apertured to receive rivets 12 or other suitable fastening

units by which the bracket is secured in place on the rail.

Connected to the bridge piece 11' and the upper and lower plates is a web 13 which is disposed centrally of the bracket and extends for a short distance longitudinally thereof. The web may be provided with 60 an aperture 13' to permit the passage therethrough of a bolt 14 by means of which legs 15 are pivotally secured to the rail and serve to support the rail when the caisson is detached from the vehicle which it has been 65 trailing.

At the forward end of the bracket 11, a depending offset 16 is formed which is bored and countersunk at 17 to receive the shank 18 of a lunette 19 through which 70 lunette the rail may be coupled to a vehicle. The end of the shank 18 is threaded as at 20 to receive a nut 21 by which the shank is firmly bound in the offset 16.

It is believed that the operation of the 75 device will be amply understood from the foregoing description without a separate and detail explanation thereof.

Having described my invention, what I 80 claim as new and desire to secure by Letters Patent is:—

1. A lunette bracket including upper and lower plates, said plates provided with apertures for the reception of fastening means, a bridge piece connecting the forward ends of the plates, a web connected to the bridge piece and the plates and positioned centrally of and extending longitudinally of the bracket, said bridge piece provided with an aperture, an offset depending from the forward end of the bracket, said offset bored and countersunk, a lunette having a shank formed to fit in the bore of the offset, and means for binding the shank in place in the bore. 90

2. A lunette bracket, including upper and lower plates, said plates provided with apertures for the reception of fastening means, a bridge piece connecting the forward ends of the plates, a web connected to the bridge piece and the plates and positioned centrally of and extending longitudinally of the bracket, an offset depending from the forward end of the bracket, said offset provided with a longitudinal bore, a 100 lunette having a shank formed to fit in

the bore and means for binding the shank in place.

3. A lunette bracket, including upper and lower plates, a bridge piece connecting the forward ends of the plates, a web connected to the bridge piece and the plates and an offset formed on and depending from the forward end of the bracket, said offset provided with a longitudinal bore, a lunette 10 having a shank formed to fit in the bore and means for binding the shank in place.

4. A lunette bracket, including spaced apart plates adapted for attachment to the

center rail of a caisson, an offset depending from the forward end of the bracket, said 15 offset provided with a bore, a lunette having a shank to fit in the bore and means for binding the shank in place.

5. A lunette bracket, including a part adjustable to the center rail of a caisson, an 20 offset depending from the bracket, said offset provided with a bore, a lunette having a shank formed to fit the bore and means for binding the shank in place.

LOUIS B. CRAIG.
